[57] CLAIM

The ornamental design of the woman's shoe, substantially as shown and described.

DESCRIPTION

FIG. 1 is a right side elevational view of a woman's shoe showing my new design;

FIG. 2 is a front elevational view;

FIG. 3 is a rear elevational view;

FIG. 4 is a left side elevational view;

FIG. 5 is a bottom plan view;

FIG. 6 is a top plan view; and,

FIG. 7 is a front to right perspective view.

The characteristic feature of the design resides in the configuration of the sole, from front tip to heel.

FIG. 1

FIG. 2

FIG. 3

FIG. 4

FIG. 5

FIG. 6

FIG. 7
